ABRASIVE SUPPLY SYSTEM

Charles M. Gossard, Hagerstown, Md., assignor to Pangborn Corporation, Hagerstown, Md., a corporation of Maryland

Original application April 27, 1942, Serial No. 440,689. Divided and this application February 29, 1944, Serial No. 524,495

4 Claims. (Cl. 51—12)

The present invention relates to apparatus for replenishing the abrasive particles supplied to devices or machines for projecting such particles at abrading or blasting velocities and more particularly pertains to means for automatically controlling the addition of new or fresh particles to the abrasive in a system circulating abrasive particles through abrasive projecting apparatus. This application is a division of application Serial No. 440,689, filed April 27, 1942.

A conventional system for supplying abrasive to apparatus for projecting the particles usually includes a bin in which a main supply of abrasive is stored. The machine or device for projecting the abrasive particles at an abrading or blasting velocity is usually mounted below the main bin so that the particles may flow downwardly therefrom into a position for being acted on by the propelling apparatus. The prior arrangements often include means for recovering the spent particles projected by the machine or blast nozzles and means for returning the collected particles to the main bin or hopper for recirculation through the abrading or blasting apparatus. The impingement of the particles on articles to be cleaned or abraded, or on the surface of the material to be treated, causes some of the particles to be broken, and further recirculation of the abrasive particles in such substantially closed circuit supply system will cause further particles to be broken whereby substantial disintegration takes place and new or fresh abrasive must be added to the main bin. It has been customary in the past to add sufficient new or unbroken abrasive particles to the main bin at the beginning of a blasting or abrading operation so that the articles or material blasted or abraded immediately thereafter are engaged by unbroken particles, but later during operation the articles or material are blasted or abraded with broken or smaller particles. Thus, the abrading or blasting operations carried out with the prior arrangements do not provide a uniform treatment of the surface of the articles or material being abraded or blasted.

It is therefore an object of the present invention to avoid material or detrimental variations in the character of the abrasive material by automatically adding abrasive particles to the abrasive supply circuit and thereby maintain the abrasive in the system at a substantially uniform degree of brokenness. Thus, different articles or materials blasted or abraded throughout an extended period are thereby provided with a more uniform treatment.

A further object of the invention resides in providing means for automatically controlling the admission of abrasive particles from an auxiliary supply to the system feeding abrasive to the projecting apparatus and in such a manner that the new abrasive will be mixed with or distributed throughout the used abrasive.

Other objects and features of the invention will be more apparent to those skilled in the art upon a consideration of the accompanying drawing and the following detailed description wherein an exemplary embodiment of the invention is disclosed.

The drawing is a diagrammatic view showing an organization of apparatus embodying the invention and illustrating means for controlling movement of particles from an auxiliary supply to the main abrasive circuit.

Referring to the drawing, there is shown at 10 a main bin for receiving and storing a supply of particles suitable for an abrading or blasting operation. The abrasive stored in the bin 10 may be of any type such as metal particles, steel shot, sand or other suitable granular material. The apparatus includes means for guiding the abrasive from the main bin 10 downwardly into apparatus for projecting the abrasive particles. Such guide means may take the form of a feed spout or conduit 11 for directing or guiding the abrasive into an operative position in relation to the projecting apparatus shown generally at 12. Any type of machine or device may be employed for projecting the abrasive particles, and for the purposes of illustration only a rotor or wheel is shown for accelerating the abrasive and projecting the abrasive particles onto articles to be cleaned or abraded. The abrasive projecting apparatus may include a rotor as disclosed in the patent to Keefer, No. 2,108,005, having a series of blades for projecting the abrasive particles in any direction, and in one example the abrasive stream is directed downwardly as indicated by the dotted lines 14 blasting articles such as a plurality of castings 16.

The projected abrasive particles are collected and returned to the main bin 10 by any suitable means which may include a housing 17 having sloping side walls, worm conveyor means shown at 18 and an elevator type conveyor means indicated generally at 19. The worm conveyor 18 may be mounted in any conventional manner so as to move the spent abrasive particles into the casing of the elevator 19. The elevator may also be of a conventional type including, for example, an endless chain carrying cups or buckets 21 whereby the used particles are returned to the

main bin 10 for recirculation through the abrading or blasting apparatus 12. The worm conveyor 18 and the elevator 19 may be driven by any suitable source of power (not shown). Appropriate means not shown may also be provided for driving the abrasive projecting apparatus 12. A main abrasive supply circuit is thus provided for guiding the abrasive particles from the main bin 10 to the abrasive projecting apparatus 12 and collecting and returning the projected particles to the main bin by the conveyor means 18 and 19.

The impingement of the abrasive particle on the articles 16 will cause some of the particles to be broken, and further recirculation of the broken abrasive particles will result in further breaking of such partly broken particles so that eventually some of the abrasive will be lost from the system in the form of dust. In addition to the disintegration of the abrasive, other particles will escape from the system so that the supply will be steadily depleted. The invention includes means for automatically adding abrasive particles to the main supply circuit when the particles stored in the main bin or hopper 10 are depleted below a predetermined quantity, or below a predetermined level, whereby the abrasive in the main bin is replenished before the bin 10 is completely exhausted.

In carrying out the invention, the abrasive is preferably added to the main abrasive circuit, such as to the conveyor means 18. The means for admitting abrasive particles to the conveyor 18 from a replenishing bin 60 is only operable when the abrasive in the main bin 10 falls below a predetermined level, or below the dotted lines shown in the drawing. An auxiliary supply of abrasive particles may therefore be stored in the replenishing bin 60 so as to be normally guided into the conveyor 18 by means of a conduit 61 in open communication with the conveyor 18. The conduit 61 is preferably formed of non-magnetic material. The downward movement of abrasive particles from the replenishing bin 60 may be interrupted or blocked by any suitable means, such as an inductive coil 62, which may, for example, surround the conduit 61, and when this coil is energized magnetizable abrasive particles such as steel shot will be blocked by the flux set up by the magnetic field provided by the coil 62.

The embodiment of the invention shown in the drawing includes means for rendering such blocking means operative. Thus, an electrical source indicated at 63 may be provided, coupled with a circuit 64 and means for closing the supply source across the coil 62 when the abrasive stored in the main bin 10 is above a predetermined quantity. The circuit 64 may be closed by any suitable means such as a stationary contact member 66 which may be engaged by a movable contact member 67. These contacts are preferably arranged to be normally open, and the contact member 67 is pivotally mounted at 68. The contacts may be moved to a closed position by any suitable means such as a permanent magnet 69 which is drawn to the right when the particles stored in the main hopper 10 are above a predetermined level. For this purpose the abrasive particles are of a magnetizable character and the main bin 10 is provided with a non-magnetic portion 71.

In operation of this arrangement the abrasive particles from the main supply or main bin 10 flow downwardly through the guide means or

feed spout 11 into the abrasive projecting apparatus 12, and the projected particles are returned to the main bin 10 for recirculation through the projecting apparatus by means of the conveyor 18 and the elevator 19. As long as the abrasive in the main bin 10 is above a predetermined level the magnet 69 will remain attracted to the magnetizable particles in the main bin and to the right in the drawing, so that the contacts 66 and 67 will be closed to supply current to the coil 62. The flux set up by the inductive coil 62 will magnetize the particles in the non-magnetic conduit 61 and block downward movement of the abrasive particles through the conduit means 61. When the abrasive in the main bin 10 falls below a predetermined level the magnet 69 will no longer be attracted to any magnetizable material and the contact member 67 will swing to the left and the coil 62 will be de-energized. Thereafter the abrasive from the replenishing bin 60 may flow into the conveyor means 18 through the conduit 61 and be elevated into the main bin 10.

While the invention has been described with reference to specific structural details such as the pipes and conduits, it will be appreciated that changes may be made therein by those skilled in the art. Such modifications and alterations in the electrical features described may be made without departing from the spirit and scope of the invention as set forth in the appended claims.

I claim:

1. In abrasive blasting apparatus, a main bin for storing abrasive particles, abrasive projecting apparatus, means providing a circuit for guiding abrasive particles from said bin to the abrasive projecting apparatus and returning the projecting particles to said bin, an auxiliary source of abrasive particles, means for guiding particles from said auxiliary source downwardly into said circuit, means for interrupting the downward movement of particles in said guide means, a source of current, a circuit for connecting said source to said means, and means actuated when a predetermined quantity of abrasive is present in the main bin for controlling said circuit and thereby rendering said interrupting means operative.
2. In abrasive blasting apparatus, a main bin for storing a supply of abrasive particles, abrasive projecting apparatus, means providing a circuit for guiding abrasive particles from said bin to the abrasive projecting apparatus and returning the projecting particles to said bin, a replenishing bin for receiving a supply of abrasive particles, a conduit extending downwardly from said replenishing bin for depositing particles therefrom into said circuit, an electro-magnetic valve for interrupting the movement of particles in said conduit, an electrical source, an electrical circuit including therein said source and said electro-magnetic valve, and means for closing said electrical circuit to said electro-magnetic valve when the quantity of abrasive stored in the main bin is above a predetermined amount.
3. In abrasive blasting apparatus, a main bin for storing magnetizable abrasive particles, abrasive projecting apparatus receiving particles from said bin, means collecting the projected particles, conveyor means returning the collected particles into said main bin, a replenishing bin for storing a supply of magnetizable abrasive particles, a non-magnetic conduit for guiding particles from the replenishing bin into said conveyor

means, an inductive coil adjacent said conduit, a magnet movably mounted adjacent an upper portion of said main bin so as to be moved when sufficient magnetizable particles are stored in the main bin, and means for supplying current to said coil upon movement of said magnet whereby flux set up by said coil magnetizes the abrasive particles in said conduit to block movement of abrasive therein.

4. In abrasive blasting apparatus, a bin for 10 storing abrasive particles, abrasive projecting apparatus, means providing a circuit for guiding

abrasive particles from said bin to the abrasive projecting apparatus and returning the projected particles into said bin, means for feeding abrasive particles from an auxiliary source into said circuit, means for interrupting the movement of abrasive particles from the auxiliary source into said circuit, and means operable upon the presence of a predetermined quantity of abrasive in said bin for rendering said interrupting means operative.

CHARLES M. GOSSARD.
